DRINKING TUMBLER OR THE LIKE

Jack Bloch, Leominster, Mass., assignor, by mesne assignments, to Foster Grant Co., Inc., Leominster, Mass., a corporation of Delaware

Filed Feb. 14, 1957, Ser. No. 44,873

Term of patent 14 years

(Cl. D36—8)

FIG. 3

FIG. 1

FIG. 4

FIG. 5

FIG. 2

Fig. 1 is a front elevational view of a drinking tumbler or the like, showing my new design;

Fig. 2 is a bottom plan view;

Fig. 3 is a fragmentary vertical sectional view taken on the line 3—3 of Fig. 2;

Fig. 4 is a fragmentary vertical sectional view taken on the line 4—4 of Fig. 2; and

Fig. 5 is a fragmentary vertical sectional view taken on the line 5—5 of Fig. 2.

I claim:

The ornamental design for a drinking tumbler or the like, substantially as shown.
